CARTON

Harry A. Inman, Newark, N. Y.

Application August 26, 1933, Serial No. 686,965

2 Claims. (Cl. 229—29)

This invention relates to cartons and more particularly to egg cartons.

An object of the present invention, is to provide a collapsible carton formed from a minimum amount of sheet material, which carton possesses a high degree of strength and provides a substantial amount of cushioned protection for the articles contained therein.

Another object of the invention, is to produce a carton provided with a V-shaped or cushioned bottom and having in intersecting planes, partitions of such shape and arrangement as to afford a high degree of resistance to a crushing force.

A further feature of the invention relates to a novel arrangement for locking a tongue formed of sheet material in a slot in sheet material.

For a clearer understanding of the invention, reference is made to the drawing in which Fig. 1 represents a blank which may be folded to form certain of the walls of a carton and certain of the transverse partitions forming a part thereof; Fig. 2 illustrates a longitudinal partition which engages with the transverse partitions and with the bottom of the carton blank of Fig. 1 to hold these parts in position for use; Fig. 3 is a perspective view of the carton ready for use; Fig. 4 represents an end view of the carton in its erected condition; Fig. 5 illustrates the carton in its collapsed condition with a portion of the cover broken away; and Fig. 6 is a fragmentary bottom view of the assembled carton illustrating how the tongues of the longitudinal partition are locked in slots in the bottom section.

Referring especially to Fig. 1, there is represented a blank of cardboard or other suitable sheet material including latch strip 6, cover 7, rear section 8, bottom section 9, front section 10, transverse partitions 11 and fastening strip 12. As herein shown the width of the cover 7 as well as the greatest length of the partitions 11 are greater than the width of the bottom section 9. It will be noted that the latch strip 6 and the cover 7 are joined together by material at the line of scoring 13, while the material at the line of scoring 14 connects the cover to the rear section 8. Lines of scoring 15 and 16 define the bottom section with respect to the rear section 8 and the front section 10. The bottom section is provided with a longitudinal line of scoring 18 and with spaced slots 19 in alignment therewith to permit the central portion of the bottom section to be elevated, thereby providing two inclined portions joined at this

line of scoring. The slots 19 are of substantial width and the righthand end of each slot as shown in Figs. 1 and 6, is closed by two opposing tabs 20 and 21, formed by cutting the material of the blank along lines 22, 23 and 24, as well as along lines 25 and 26. These tabs may be of equal length although as herein illustrated tab 21 is longer than tab 20 to extend across the line of scoring 18. The function of the tabs 20 and 21 of unequal length, as well as the purpose of having the slot 20 of a substantial width will be hereinafter set forth.

The transverse partitions 11 are cut free from the remainder of the blank along lines 27 and 28, inclined toward the edges of the blank, except that the upper corners of each partition is integral with triangular connecting pieces 29 being connected to these pieces by the material scored at the score lines 30. These triangular connecting pieces are also integrally connected to front section 10 and to the connecting strip 12 by the material scored along the lines 31. Each triangular connecting piece is provided with a line of scoring 32 extending from the free margin of the piece to its opposite apex to permit the carton to be collapsed. Although it is preferred to provide the lines of scoring 30, 31 and 32 to define the triangular connecting pieces, it will be understood that the blank may be folded along these lines even if the blank is not originally provided with this scoring.

It will be noted from Fig. 1 that the lefthand or bottom edges 33 of the transverse partitions are cutout in V-shaped formation, while the righthand edges 34 of these partitions are likewise of general V-shaped outline, except that the apexes thereof are cut off as indicated at 35 to provide straight edge portions in a plane common with the top of the carton when assembled. The two outside or end partitions are provided with the kerfs 36 while the intermediate partitions are provided with kerfs 36 and 37 extending in alignment respectively from the top and bottom edges of these partitions when the carton is assembled. Lines of scoring 38 together with the several kerfs permit these partitions to be folded transversely on themselves when the carton is collapsed for shipping.

The carton is also provided with a longitudinal partition 39 of the general outline indicated in Fig. 2 which partition is provided with transverse slots 40 near its ends and with intermediate transverse slots 41, the entrances to which intermediate slots are restricted by the tabs 42. The longitudinal partition is also provided at its

lower edge with tongues 43 to engage the respective slots 19 in the bottom section 9 when the carton is assembled. Each of the tongues has a lateral locking notch 44 at the junction 5 of the tongue with the longitudinal partition. It should be mentioned that the width of the tongues 43 at their notches 44, is slightly less than the length of the slots 19 in the bottom section. The number of tongues 43 and the 10 number of related slots 19 are preferably such that these tongues support the bottom section at points between each pair of transverse partitions.

In completing the carton ready for shipment, 15 the blank is folded into rectangular form along the lines of scoring 14, 15, 16 and the scoring lines 31 of the triangular connecting pieces at both sides of the transverse partitions. The free edge of the fastening strip 12 is turned down- 20 ward and this strip is then glued or otherwise fastened to the back section 8 as shown in Fig. 4. The transverse partitions are then folded down- 25 ward at right angles to the bottom section 9 by folding on the lines of scoring 30. Thereafter, the longitudinal partition 39 is assembled into 30 the carton by inserting the transverse partitions 11 into the respective slots 40 and 41 of this partition until the body of the partition engages the bottoms of the kerfs 36 in the transverse 35 partitions. The tabs 42 then enter the kerfs 37 in the bottom edges of the intermediate trans- 40 verse partitions to lock the longitudinal partition thereto.

With the parts thus formed, the carton may 35 be collapsed into flat condition (as shown in Fig. 5) by folding the portions of the bottom section 9 along the line of scoring 18 away from the remainder of the carton and by moving the longitudinal partition 39 to the right (Fig. 5) 40 while folding the connecting pieces on the lines of scoring 32 and while doubling both portions of each transverse partition 11 toward each other along the line of scoring 38. With the carton in this flat condition, as shown in Fig. 5, it may 45 be shipped to the ultimate consumer who can form it ready for use as shown in Fig. 3, merely by moving the longitudinal partition 39 endwise until the tongues 43 thereon can be inserted through the slots 19 in the bottom section of the 50 carton after it has been raised to the position as shown in Fig. 4. Since the width of the tongues 43 is greater than the length of the slots 19, the tabs 20 and 21 must be forced downward to 55 permit these tongues to enter the respective slots and to pass between these tabs. When, however, the tongues are completely inserted into the slots and moved to the left until the material at the left end (Fig. 6) of the slots engages the notches 44 of the tongues, the tabs 20 and 21 due to 60 their substantial resilience return to their normal positions where their exposed edges can engage the adjacent edges of the tongues. It has been

mentioned that slots 19 have a substantial width and that tab 21 is longer than tab 20 with the tab 21 extending across the line of scoring 18. With this construction, when the carton is erected, the tongues 43 on the longitudinal partition 39 will tend to position themselves in approximate alignment with the fold at the score line 18 so that these tongues will tend to assume the position shown in Fig. 6, that is with right hand edges of the tongues engaging the long 10 tabs 21 so that there is very little chance for these tongues to enter the cuts 23 accidentally. The latch strip 6 has hook-shaped tongues 45 which are adapted to engage the triangular connecting pieces 29 at the front of the carton so 15 that the cover may be latched in closed position as shown in Fig. 4. It will be understood that even if the tabs 20 and 21 are of equal length, the tongues will be retained in the slots 19 until intentionally removed therefrom. This arises 20 from the fact that the ends of a pair of tabs 20 and 21 are substantially in engagement so that the right hand edge of the tongue will engage the exposed edge of either one or both of 25 said tabs without entering the cut 23. 25

What I claim is:

1. In an arrangement for locking a strip of sheet material at an angle to a piece of sheet material folded in V-shaped form, said piece having an elongated slot therein of substantially 30 greater width than the thickness of the material of said strip, said slot being symmetrical with respect to and having its greatest dimension extending in the direction of the axis of said fold, said piece being provided with two opposing tabs 35 defining one end of said slot and having their ends in substantial engagement, said tabs being of unequal length so that one tab extends across said fold, said strip having a tongue with a lateral notch therein, said tongue at one portion thereof 40 having a width greater than the length of said slot and the portion of said tongue at said notch having a width slightly less than the length of 45 said slot.

2. In an arrangement for locking a strip of sheet material at an angle to a piece of sheet material folded in V-shaped form, said piece having an elongated slot therein extending along said fold, said piece being provided with a tab 50 extending across at least a portion of one end of said slot, said tab being bendable about an axis parallel to and spaced from said fold and being of a length to extend across said fold, said strip having a tongue with a lateral notch therein, said tongue at one portion thereof having a width 55 greater than the distance from the free edge of said tab to the opposite end of the slot, and the portion of said tongue at said notch having a width slightly less than the distance from the free edge of said tab to the opposite end of said 60 slot.

HARRY A. INMAN.
